UNITED STATES PATENT OFFICE.

CLEMENT G. HARRINGTON, OF MAPLEWOOD, MISSOURI, ASSIGNOR TO AMERICAN CAR & FOUNDRY COMPANY, OF ST. LOUIS, MISSOURI, A CORPORATION OF NEW JERSEY.

TANDEM-SPRING DRAFT-RIGGING.

No. 918,851.

Specification of Letters Patent. Patented April 20, 1909.

Application filed January 31, 1908. Serial No. 413,576.

To all whom it may concern:

Be it known that I, CLEMENT G. HARRINGTON, a citizen of the United States, residing at Maplewood, St. Louis county, Missouri, have invented a certain new and useful Improvement in Tandem-Spring Draft-Rigging, of which the following is a full, clear, and exact description, such as will enable others skilled in the art to which it appertains to 10 make and use the same, reference being had to the accompanying drawings, forming part of this specification, in which—

Figure 1 is a top plan view partly in section of a draft rigging constructed in accordance with my invention; Fig. 2 is a side elevation of said draft rigging, the intermediate stop being shown in section; Fig. 3 is a cross sectional view taken on the line 3—3 of Fig. 1, the springs not being shown; and Fig. 4 is 20 a detail perspective view of one of the intermediate followers.

This invention relates to draft rigging for railway cars, and particularly to tandem-spring draft riggings.

25 The main object of my invention is to provide a draft rigging of the type referred to that is of simple construction and which will effectively absorb buffing and pulling shocks.

Referring to the drawings which illustrate 30 the preferred form of my invention, 1 designates draft sills or continuous center sills of a car underframe, and 2 designates end stops on said sills which coöperate with the end followers of the draft rigging. An intermediate stop is arranged between the stops 2, 35 and said intermediate stop preferably consists of a ribbed casting 3 that extends transversely between the draft sills and is rigidly connected thereto by bolts or rivets 4 that 40 pass through said parts and also by means of rivets 4^a that pass through the lower flanges of the draft sills and laterally projecting flanges 3^a on the casting, as shown in Fig. 3. Intermediate followers 5 are arranged on 45 opposite sides of this intermediate stop 3, and end followers 6 coöperate with the end stops 2, the reference characters 7 designating the tandem-arranged springs that are interposed between the followers of each pair.

50 The yoke or strap 8 on the drawbar 9 surrounds the end followers and intermediate followers and is provided with elongated slots 8^a that receive vertically disposed projections on the intermediate followers 5. 55 Each of said intermediate followers consists

of a cylindrical-shaped casting provided with a thick vertically disposed central web 10 and webs 11 that project radially therefrom, as shown in Fig. 4, the casting being provided at one end with a solid wall 12 which 60 carries a hollow boss 13 that centers the springs. The vertically disposed projections on each of the intermediate followers 5 preferably consist of a flat pin 14 that extends through an opening 15 in the vertically 65 disposed central web 10 of the follower, said pin being provided at its upper end with a head 14^a which rests upon the drawbar yoke, as shown in Fig. 3. The pin 14 is retained in position by means of a cotter 16 that passes 70 through an opening in the lower end thereof below the drawbar yoke.

Under buffing strains the end follower 6 of the front set of springs, namely, the set that is arranged in front of the intermediate stop 75 3, will move rearwardly and thus compress said springs against the intermediate follower 5 of said set which is held stationary by the intermediate stop 3, and the intermediate stop 5 of the rear set of springs will 80 be moved rearwardly to compress said springs when the pin 14 on said follower is engaged by the front end of the slots 8^a in the drawbar yoke into which said pin projects, the end follower of the rear set of 85 springs being held stationary by the end stops 2 on the draft sills with which said follower coöperates. Under pulling strains the intermediate follower 5 of the rear set of springs will be held stationary by the intermediate stop 3, and the intermediate follower 5 of the front set of springs will be 90 moved forwardly when the pin 14 on said follower is engaged by the rear ends of the slots 8^a in the yoke into which said pin projects. 95

A construction of this character forms a very efficient draft rigging and can also be manufactured at a low cost.

Having thus described my invention, what 100 I claim as new and desire to secure by Letters Patent is:

1. A tandem spring draft rigging comprising an intermediate stop, followers arranged on opposite sides of said stop, a drawbar yoke 105 surrounding said followers and provided with elongated slots, and vertically disposed projections carried by the intermediate followers and movable therewith and projecting into said elongated slots so as to transmit the 110

- movements of the drawbar to said followers; substantially as described.
2. A tandem spring draft rigging comprising an intermediate stop secured to the draft sills of the underframe, followers arranged on opposite sides of said stop, a drawbar yoke, and removable pins passing through said followers and projecting into slots in said yoke so as to transmit the movements of the yoke 10 to said followers, said pins being so constructed that they move with the followers; substantially as described.
3. In a tandem spring draft rigging, an intermediate stationary stop, intermediate followers arranged on opposite sides of said stop, a drawbar yoke provided with elongated slots, and vertically disposed removable pins carried by the intermediate followers and projecting into said slots and provided at their upper ends with heads which rest on the drawbar yoke, said pins operating to transmit the movements of the drawbar to said followers; substantially as described.
4. In a tandem spring draft rigging, an intermediate stationary stop, intermediate followers arranged on opposite sides of said stop, a drawbar yoke provided with elongated slots, pins carried by the intermediate followers and movable therewith, said pins 30 projecting into the slots of the yoke, heads on the upper ends of said pins which rest on the yoke, and means for preventing said pins from being displaced from said followers; substantially as described.
5. In a tandem spring draft rigging, flanged draft sills, an intermediate stop extending transversely between said sills and provided with laterally projecting flanges that contact with the flanges on the draft sills, and fasten-
ing devices passing through the body portion 40 of said stop and through said draft sills and also through the flanges on said stop and sills; substantially as described.
6. A follower for a draft rigging consisting of a cylindrical-shaped casting provided with 45 a thick central web extending transversely thereof, and a plurality of webs projecting radially from said central web; substantially as described.
7. A follower for a draft rigging consisting of a cylindrical-shaped casting provided at 50 one end with a solid wall, a thick central web extending transversely of said casting, and a plurality of webs projecting radially from said central web; substantially as described.
8. A follower for a draft rigging consisting of a cylindrical-shaped casting provided at one end with a solid wall which has a spring-centering boss formed integral therewith, a thick central web extending transversely of 60 said casting and having an opening extending longitudinally therethrough, webs projecting radially from said central web and integrally connected to the outer wall of the casting, and a pin arranged in the opening in said central web and conforming to the cross sectional shape thereof so that it will move with the follower, said pin projecting beyond the edges of the follower; substantially as described.
- 70
In testimony whereof I hereunto affix my signature in the presence of two witnesses, this twenty ninth day of January, 1908.
- CLEMENT G. HARRINGTON.
